UNITED STATES PATENT OFFICE.

EJNAR FABRICIUS-BJERRE, OF FREDERIKSBERG, NEAR COPENHAGEN, DENMARK.

ABSORBENT PAD.

Application filed February 20, 1924. Serial No. 694,113.

To all whom it may concern:

Be it known that I, EJNAR FABRICIUS-BJERRE, citizen of the Kingdom of Denmark, and residing at Frederiksberg, near

5 Copenhagen, Denmark, have invented certain new and useful Improvements in Absorbent Pads, of which the following is a specification.

This invention relates to the production 10 of a liquid-absorbing gauze-like fibrous pad from a known fibrous or cellular material, say cellulose wadding, peat fibres, felt, waste sponges, or the like which is covered on one or both sides by crossing threads forming 15 a gauze-like surface and entering into an inseparable connection with the fibrous material so that the latter cannot during its use be decomposed by soaking or otherwise.

20 The fibrous material may be treated in a known manner in different ways, that is it may be sterilized, freed from grease in order to increase its absorbing ability, or weakened by mechanical or chemical treatment.

25 The material must be such that it may be mechanically manufactured, that is, the fibrous or cellular mass is at first in the way known from the manufacture of paper 30 or by spinning machines formed into an endless belt of a suitable width and thickness, and, thereafter, rolled or folded together so as to give the ready material its proper shape and thickness. Further 35 the material is sewed by crossing threads in a special machine so as to produce the above mentioned gauze-like covering, and subsequently cut or stamped out to obtain a shape corresponding to the purpose in question. Finally it is provided with sewed or 40 bound straps, bands or the like in order to enable it to be secured, and it is then ready for use.

45 The above mentioned various mechanical treatments of the material may be carried out in one single machine, or the material may pass several machines each performing one of said treatments.

50 The invention is clearly illustrated in the accompanying drawing, in which:—

Fig. 1 is a top plan view of a portion of the material,

Fig. 2 is the bottom plan view thereof,

Fig. 3 is a transverse section through the 55 material, and

Fig. 4 is a transverse section through a modified form of the invention employing two layers of the material one of which is water-proof.

Referring now, more particularly, to the 60 accompanying drawing there is provided a pad *a* of fibrous material through which threads *b* are drawn so as to form on the engaging surfaces a gauze-like covering inseparably connected with the material. 65 Preferably the stitching is made in such a manner that rows of chain stitches are laid in one direction and loose threads are arranged below and engaged by said stitches on the engaging surfaces of the material 70 and preferably intersecting said chain stitches at right angles so as to form substantial squares as indicated in the drawings.

In Fig. 4 there is shown a slightly modified arrangement comprising superposed layers *a'* and *a''*, the layers being of an absorbent nature while the layer *a''* is impregnated in a known manner so as to be rendered water-proof, the purpose being to 75 prevent the liquid absorbed by the layer *a'* from penetrating through the layer *a''*. The threads *b'* are arranged in the same manner as described in connection with 80 Figs. 1 and 2 being of course passed through both of said layers so as to hold them together. The pads, as intimated, are provided with a binding or band *c* along the 85 marginal edges so as to prevent the material from fraying at said edges.

The fibrous material treated as above is intended for use in the sick nursing as dressing, operating serviettes, catamenial sacks, child's napkins, breast napkins for nursing ladies, towels, handkerchiefs, and 90 in the general in all cases where a great absorbing ability is important.

After the use the gauze-like fibrous material is discarded which is an invaluable advantage in hygienic respect. As the 100 fibrous material may be delivered in a sterile state, it will be preferred in many cases to other materials used hitherto.

A special employment of the material is for child's napkins. Experience has shown 105 that a child's napkin of this gauze-like fibrous material having a lesser weight than a napkin of the best suited materials hitherto known is as good as two such napkins.

Having thus fully described the inven- 110

tion what is claimed as new and desired to be secured by Letters Patent is:—

1. A device of the character described including a pad-like body formed of absorbent fibrous material of suitable shape and thickness, and a gauze-like covering of cross threads arranged on one side only of the pad-like body with threads of the covering entering into an inseparable connection 10 with the pad-like body.

2. A pad of the character described formed of a layer of an absorbent fibrous material of suitable shape and thickness, a waterproof layer of fibrous material arranged adjacent one surface of the absorbent

layer, and a gauze-like covering of cross threads arranged on one face only of the absorbent layer with threads of the covering entering into an inseparable connection with the layers so as to hold them together. 20 substantially as and for the purposes set forth.

3. A device as claimed in claim 1, wherein bindings are secured to certain edges of the pad-like body to prevent unraveling and 25 fraying of the material at said edges, substantially as and for the purposes set forth.

In testimony whereof I affix my signature.

EJNAR FABRICIUS-BJERRE.
